(57) **CLAIM**

We claim the ornamental design for a cabinet, as shown and described.

DESCRIPTION

FIG. 1 is a perspective view of a cabinet of the new design; FIG. 2 is a side view of the cabinet of FIG. 1, the other side view being a mirror image;

FIG. 3 is a front view of the cabinet of FIG. 1;

FIG. 4 is a back view of the cabinet of FIG. 1;

FIG. 5 is a top view of the cabinet of FIG. 1;

FIG. 6 is a bottom view of the cabinet of FIG. 1;

FIG. 7 is a perspective view of the cabinet of FIG. 1, wherein the drawers are extended;

FIG. 8 is a perspective view of another embodiment of the new design;

FIG. 9 is a side view of the cabinet of FIG. 8, the other side view being a mirror image;

FIG. 10 is a front view of the cabinet of FIG. 8;

FIG. 11 is a back view of the cabinet of FIG. 8;

FIG. 12 is a top view of the cabinet of FIG. 8;

FIG. 13 is a bottom view of the cabinet of FIG. 8;

FIG. 14 is a perspective view of the cabinet of FIG. 8, wherein the drawers are extended;

FIG. 15 is a perspective view of yet another embodiment of the new design;

FIG. 16 is a side view of the cabinet of FIG. 15, the other side view being a mirror image;

FIG. 17 is a front view of the cabinet of FIG. 15;

FIG. 18 is a back view of the cabinet of FIG. 15;

FIG. 19 is a top view of the cabinet of FIG. 15;

FIG. 20 is a bottom view of the cabinet of FIG. 15;

FIG. 21 is a perspective view of the cabinet of FIG. 15, wherein the drawers are extended;

FIG. 22 is a perspective view of yet another embodiment of the new design;

FIG. 23 is a side view of the cabinet of FIG. 22, the other side view being a mirror image;

FIG. 24 is a front view of the cabinet of FIG. 22;

FIG. 25 is a back view of the cabinet of FIG. 22;

FIG. 26 is a top view of the cabinet of FIG. 22;

FIG. 27 is a bottom view of the cabinet of FIG. 22; and,

FIG. 28 is a perspective view of the cabinet of FIG. 22, wherein the drawers are extended.
